A. DI IOIA

CHALKING DEVICE

Filed April 25, 1925

Patented Oct. 5, 1926.

1,602,219

UNITED STATES PATENT OFFICE.

ALBERT DI IOIA, OF PHILADELPHIA, PENNSYLVANIA.

CHALKING DEVICE.

Application filed April 25, 1925. Serial No. 25,961.

My invention relates to a new and useful chalking device particularly adapted for marking or chalking furs or the like.

My invention relates more particularly to 5 a novel chalking device having a suitable stencil or marking edge, a chalk container, and means to guide said chalk container above said marking or stencil edge so that it may be brought down upon such edge for 10 the purpose of drawing a mark on the fur along such marking or stencil edge.

With the above ends in view, my invention 15 consists of a stencil plate having any desired ruling, marking or stencil edge, a guide-way integral with said plate and extending along, and co-extensive with said edge, a longitudinal slide mounted in said guide-way and adapted to travel therein, a vertical slide carried by said longitudinal slide and a 20 chalk container, open at its bottom, carried by said vertical slide, in vertical alignment with the stencil edge of said plate, whereby the container may be brought down into contact with the stencil edge and the fur beneath the same.

For the purpose of illustrating my invention, I have shown in the accompanying drawings forms thereof which are at present preferred by me, since they will give in practice satisfactory and reliable results, although it is to be understood that the various instrumentalities of which my invention consists can be variously arranged and organized and that my invention is not limited 35 to the precise arrangement and organization of these instrumentalities as herein shown and described.

Referring to the drawings in which like reference characters indicate like parts:—

40 Figure 1 represents a plan view of a chalking device embodying my invention.

Figure 2 represents a rear elevation of the same.

45 Figure 3 represents a section on line 3—3 of Figure 2.

Referring to the drawings, 1 designates a plate having any desired ruling or stencil edge 2, in the particular case a serrated edge, and a guide channel 3 extending the length 50 of the plate and projecting upwardly therefrom, said guide channel having a slot or opening 4 therein, through which a portion of the slide 5 may pass.

The slide 5 carries an upright plate 6, 55 having the guide members 7, adapted to guide in a vertical line, the vertical slide 8.

The vertical slide 8 is constantly urged upwardly by the spring 9, interposed between the slide 5 and the horizontal projection 10 of the vertical slide 8, and may be forced 60 downwardly against the force of the spring 9, by merely pressing down upon the finger knob 11. The vertical slide 8 is bent at its upper end, as at 12, to which bent portion 12, is secured, in any suitable manner, a 65 chalk container 13, cylindrically shaped and having an opening 14 at its bottom, of a somewhat smaller diameter than the diameter of the container, and which container is 70 so positioned by said vertical slide as to bring said opening 14 in a substantially vertical alignment with the stencil or marking edge 2 of the plate 1.

The chalking material 21 may be chalk dust or any other suitable powder, such as 75 corn starch, flour, or the like, and is contained within a small linen or other suitable textile bag 15, closed at its top, as shown in Figure 3. After inserting the bag 15 loosely into the container 13, a lid 16 is superimposed upon the top of the cylindrical container and is held secure thereto by means of the annular bead 17 projecting from the wall of the cylinder, and the corresponding annular groove or seat 18 in the flange 19 of 85 the lid. The lid 16 carries on its inner side a spring 20, sufficiently strong to force said linen bag 15 with the chalking powder 21 down towards the opening 14, thereby retaining a small portion of said linen bag 90 projecting through the opening 14, so that it may be brought into contact with the stencil edge 2 and the fur beneath the same.

It will thus be seen, that by means of my novel chalking device it is only necessary to 95 place the chalking device upon the material, usually fur, with the marking or stencil edge 2 along the line to be marked, holding and securing the plate 1 with one hand by merely pressing down upon it, depressing the 100 knob 11 against the force of the spring 9, thereby lowering the chalk container 13 against the stencil edge 2, and lastly, moving the chalk container and the slide 5, to and fro, guided by the guide-way 3, thus 105 leaving a mark along the fur, of the same general outline as the edge 2 of the chalking device.

It will now be apparent that I have devised a novel and useful chalking device 110 which embodies the features of advantage enumerated as desirable in the statement of

the invention and the above description, and while I have, in the present instance, shown and described a preferred embodiment thereof of which will give in practice satisfactory and reliable results, it is to be understood that such embodiment is susceptible of modification in various particulars without departing from the spirit or scope of the invention or sacrificing any of its advantages.

10 Having thus described my invention, what I claim as new, and desire to secure by Letters Patent is:—

1. In a device of the character stated, a body having a ruling edge, a guide-way substantially co-extensive with said ruling edge, a slide mounted in said guideway, a chalk holder having a bottom opening carried by said slide in substantial vertical alignment with said ruling edge, a spring normally holding said chalk holder away from said edge and means for pressing the contents of said chalk holder downwardly.

2. In a device of the character stated, a body having a ruling edge and a guide-way substantially co-extensive with said ruling edge, a longitudinally movable slide mounted in said guide-way, a vertically movable slide carried by said longitudinal slide a container having an opening in its bottom carried by said vertical slide in substantial alignment with said ruling edge, a bag of powdered marking material contained in said container, and means in said container for pressing said bag downwardly.

3. In a device of the character stated, an elongated body having a ruling edge and a guide-way substantially co-extensive therewith, a longitudinal slide mounted in said guide-way and slideable therein, a vertical slide carried by said longitudinal slide, a chalk holder having a bottom opening carried by said vertical slide in substantial vertical alignment with said ruling edge, and yieldable means urging said slide and said container out of engagement with said ruling edge.

4. In a device of the character stated, a body having a ruling edge, a guide-way substantially co-extensive with said ruling edge, a slide mounted in said guide-way, a chalk holder carried by said slide in substantial vertical alignment with said ruling edge, and having an opening at its bottom, and a fabric lining in said chalk holder for retaining therein a chalking powder.

5. In a device of the character stated, an elongated body having a serrated ruling edge and a guide-way substantially coexten-

sive with said ruling edge, a longitudinal slide mounted in said guide-way, a vertical slide carried by said longitudinal slide and a container carried by said vertical slide in substantial alignment with said ruling edge for retaining therein a chalking material.

6. In a device of the character stated, an elongated body having a ruling edge and a guide-way substantially coextensive therewith, a longitudinal slide mounted in said guide-way and slideable therein, a vertical slide carried by said longitudinal slide, a chalking material container carried by said vertical slide, in substantial vertical alignment with said ruling edge and having an opening at its bottom, a fabric bag lining said chalk container for retaining therein a chalking powder and a spring adapted to force said bag towards said bottom opening, so as to project therethrough a slight distance.

7. In a device of the character stated, a body having a ruling edge, a longitudinally extending guide way thereon, a slide movable longitudinally in said guide way, a bag of powdered marking material carried by said slide, means for normally holding the bottom of said bag normally out of contact with said ruling edge, and means for depressing said bag towards said ruling edge during the longitudinal movement of said slide.

8. In a device of the character stated, a body having a ruling edge, a slide movable longitudinally on said body, a container carried by and vertically movable upon said slide, and having an opening in its bottom, a bag of powdered marking material carried by said container, means in said container for pressing the bag towards the bottom opening in said container, means for holding said container and bag normally away from said ruling edge, and means for depressing said container and bag towards said ruling edge.

9. In a device of the character stated, a container having an opening in its bottom, and a removable lid, a bag of powdered marking material positioned in said container, a spring intermediate said lid and the top of said bag for forcing the latter downwardly, a ruling edge below the opening in said container, means for depressing said container towards said ruling edge and means for reciprocating said container with respect to said edge.

ALBERT DI IOIA.
